[57] CLAIM

The ornamental design for a pill organizer, as shown and described.

DESCRIPTION

FIG. 1 is a perspective view of a pill organizer showing my new design;

FIG. 2 is a top plan view thereof;

FIG. 3 is a right end view thereof;

FIG. 4 is a front side elevational view thereof;

FIG. 5 is a bottom plan view thereof;

FIG. 6 is a left end view thereof; and,

FIG. 7 is a rear elevational view thereof.

The portions shown in broken lines are for informational purposes only and form no part of the instant design.

The characteristic feature of the design resides in the appearance of the bottom of the organizer as shown in FIG. 5 comprising a receptacle for receiving the dosage information card shown in broken lines.

FIG. 1

FIG. 2

FIG. 3

FIG. 4
